ELECTRIFIED RAILWAY-SYSTEMS WITH FILTERED BOOSTER-TRANSFORMERS

Lloyd J. Hibbard, Pittsburgh, Pa., assignor to Westinghouse Electric Corporation, East Pittsburgh, Pa., a corporation of Pennsylvania

Application February 26, 1953, Serial No. 338,981

12 Claims. (Cl. 307—90)

My invention relates to improvements in the prevention of inductive interference in telephone lines, telegraph lines, or other communications-lines which parallel a single-phase railway-system. The novel feature of the invention is the use of a low-pass filter, or at least a fundamental-frequency filter, connected in shunt circuit relation with a booster-transformer or transformers, for forcing the voice-frequency harmonics of the electrically propelled vehicle to return through a fixed return-circuit which is so located that its inductive effects materially cancel out the inductive effects of the corresponding voice-frequency currents which are carried by the trolley-wire or power-supply line. This fixed return-circuit may be either the track-rails or an elevated pilot-wire which is adjacent to both the trolley-wire and the telephone-line.

Heretofore, in booster-transformer systems in which the secondary windings of the booster transformers were connected in series with the track-rails, and in which no filter was used, it was necessary to force the fundamental-frequency currents, as well as all of the harmonics, to flow through the rails. This has not been a very practical or desirable system, because of the necessity for limiting the maximum possible secondary voltage of the booster transformer to a value which will be safe for man and beast, even under short-circuit conditions. If this requirement is met, even for full-load conditions alone, it entails the use of many booster-transformers which are closely spaced along the right-of-way; and if the limited-voltage requirement is met when the power-circuit is short-circuited, this requirement has meant that the spacing between successive booster-transformers has had to be very small indeed.

In previous interference-eliminating systems using booster-transformers for forcing all of the return-circuit currents, both fundamental and harmonic, to flow through a pilot-wire suspended near the trolley-wire, it has been necessary to use rather large pilot-wires, in order to be able to carry the total load-currents, and in order also to have an impedance which is sufficiently low as compared to that of the track-rails.

In accordance with my present invention, the main fundamental-frequency load-current still returns through the normal rail-and-ground path, spreading out through the ground in the normal manner. This fundamental-frequency current does not usually produce any objectionable inductive interference in adjacent telephone-circuits, and if it should cause any objectionable induced noise, in telephone-lines which are unusually sensitive, the trouble can be easily eliminated by using a band-pass filter in series with the telephone line, so as to admit the flow of only the most necessary voice-transmitting frequencies, such as a band which eliminates all the frequencies below 250, 300, or 400 cycles, or the like, as is well known in telephone practice. Such a voice-frequency filter, in the telephone line, could also eliminate all extremely high-frequency harmonics, above, say, 3,000 cycles, or

2

above any other desired upper limit; or no upper limit at all could be imposed by the voice-frequency filter.

By the simple expedient of bypassing the fundamental-frequency current from the booster-transformer or transformers, I cause this transformer or these transformers to have a substantially zero fundamental-frequency secondary-voltage, thus immediately mitigating one of the big drawbacks to such booster-transformers, which is the fundamental-frequency secondary-voltage. At the same time, I reduce the size of the booster-transformers, and I reduce the necessary size of the suspended pilot or return-wire, up near the trolley, if such a wire is used, besides achieving other advantages, some of which will be pointed out in the course of the subsequent description.

In the usual case, none of the return-circuit frequencies causes objectional telephone-interference, below a certain minimum limit, which may be of the order of 250, 300 or 400 cycles; and hence, instead of using a filter which is tuned only to the fundamental frequency, for bypassing the booster-transformers, I can frequently (if not always) use a low-pass filter which substantially filters out all such low frequencies from the booster-transformer or transformers. If a voice-pass filter is used in the adjacent telephone-circuit, then the low-pass filter for the booster-transformers can materially exclude at least all frequencies which are substantially below the minimum frequency of the voice-pass filter, so that this low-frequency band is eliminated from the booster-transformer or transformers.

My invention is applicable not only to railway-systems using rectifier-powered vehicles of the type in which the single-phase power-current is rectified, in the vehicle, and delivered to direct-current traction-motors, but the invention is also applicable to single-phase railroad-systems which utilize single-phase commutator-motors for traction. All of such railway-systems produce a certain spectrum of harmonics, differing somewhat in distribution and magnitude, but always involving a more or less serious problem of inductive interference in neighboring telephone circuits. In most such single-phase railway-systems, it is feasible to design the electrical equipment which is carried by the vehicles so that no objectionable telephone-interference is encountered in most interurban or cross-country runs, and running into inductive-interference troubles only in some urban areas, or in special track-sections where the inductive-interference problem is particularly severe. My present invention makes it possible to inexpensively take care of these special inductive-interference areas, so that the entire equipment need not be designed to meet the most aggravated inductive-interference problems which exist anywhere on the railway-system.

With the foregoing and other objects in view, my invention consists in the circuits, systems, combinations, apparatus, parts, and methods of design and application, as hereinabove described, and as illustrated in the accompanying drawing, wherein the five figures show different types of illustrative forms of embodiment of my invention, in the form of simplified diagrammatic representations of different circuits and apparatus.

In Fig. 1, for example, I show an electrified railway-system, including tracks or track-rails 1, and an insulatedly supported bare or uncovered single-phase trolley-wire or power-supply line 2, and one or more substations A, each of which may include a power transformer 3 having a secondary winding 4 which is connected between the track-rails 1 and the trolley-wire 2. The trolley-wire 2 is disposed in a position suitable for supplying single-phase power to one or more electrically propelled vehicles V which ride on the tracks 1. One such vehicle is diagrammatically represented as having a pantograph 5, which is intended to be representative of any current-collecting device, including a third-rail shoe.

The vehicle-load is diagrammatically represented by the primary winding of a transformer 6, and the vehicle is further diagrammatically represented as having only one wheel 7, although it will, in general, have at least four wheels and usually many more than four wheels. It will be understood that the bare power-supply line 2 need not be an overhead trolley-wire or conductor; it may, for example, be a third rail. In the particular form of my invention which is shown in Fig. 1, however, the bare power-supply line 2 is actually a overhead trolley-wire, at least in the portion of the system which is shown in Fig. 1.

Since my invention is designed to prevent or mitigate inductive interference, it is necessarily used in a system in which there is an inductively coupled telephone-line or other communications-line or circuit 8, which is adjacent to the power-supply line 2, or to the right-of-way of the railway-system. The inductive interference arises from the fact that the tracks 1 serve jointly as a vehicle-supporting means and also, at least in part, as a ground-return means for the currents which are required by the vehicle. If all of the currents, harmonics as well as fundamental, returned through the track-rails, there would practically never be any inductive-interference problem. It is well known, however, that since the track-rails 1 are grounded, the ground-return currents spread out into the ground, leaving the rails and spreading out over a rather wide area, and then coming back into the rails again at the substation A. It is these spread-out currents, in the ground, which cause a mismatching of the inductive-interference effects of the trolley-currents and the ground-return currents, thus inducing interference-producing currents in the adjacent telephone-wires 8. More strictly speaking, it is only the spread-out harmonic ground-currents, in the voice-frequency range, which cause inductive interference in the adjacent telephone-line 8.

My invention relates broadly to any means which limits this spreading out of voice-frequency harmonic currents, while permitting the fundamental-frequency currents, or a low-frequency band including the fundamental, to spread out into the ground in the usual way, thus returning from the vehicle to the substation through a combination of rail and ground.

In the particular form of embodiment of my invention which is shown in Fig. 1, I use a special overhead auxiliary or pilot-wire or conductor 11 to provide a fixed return-circuit for the harmonics. At one or more points along the railway right-of-way, I equip both the trolley-wire 2 and the pilot-wire 11 with an insulated gap, 2' and 11' respectively. The trolley-wire gap 2' is shunted by the primary winding 13 of an iron-core booster-transformer 15. This booster-transformer has a secondary winding 17 having the same number of turns as the primary winding and insulated from the primary winding, this secondary winding 17 being connected across the pilot-wire gap 11'. At a plurality of other points along the right-of-way, the pilot-wire 11 is connected to the tracks 1 by means of a plurality of spaced track-connections 18. The idea of distance is conveyed, in the drawing, by means of dotted-line sections in accordance with a usual convention.

In accordance with my present invention, at least one of the windings of each booster-transformer 15 is shunted by a filter F. In Fig. 1, this filter F is shown as a series-resonant circuit, comprising a capacitor C and an inductance coil L, tuned approximately to the fundamental frequency of the power-supply line 2, which may, for example, be 25 cycles or 60 cycles, or even some lower frequency such as 15 cycles.

This filter F may be connected, either across the secondary winding 17 of its associated booster-transformer, as indicated by the circuit 21 in Fig. 1, or across the primary winding 13 of its booster-transformer, as indicated by the circuit 22 in Fig. 1. The secondary-circuit con-

nnection 21 has a possible advantage, in that it more perfectly keeps the fundamental-frequency current out of the pilot-wire 11, by reason of the fact that it practically short-circuits the secondary terminals 23, 24 of the booster-transformer 15. On the other hand, the primary-circuit connection 22 has the advantage of substantially completely bypassing the fundamental-frequency current around the booster-transformer 15, so that there is no fundamental-frequency terminal-voltage in this booster-transformer, either across the primary terminals 25 and 26, or across the secondary terminals 23 and 24. The voice-frequency harmonic currents, however, pass through the booster-transformer, whether it is provided with the primary filter-circuit 22 or the secondary filter-circuit 21, or both, so that the booster-transformer develops whatever voltages are necessary to cause the same voice-frequency harmonic currents to flow, in equal magnitudes and opposite directions, in the trolley-wire 2 and in the pilot-wire 11.

It will be noted that both of the filter-circuits 21 and 22, in Fig. 1, whether connected across the secondary winding 17 or the primary winding 13, have substantially the same effect with respect to the filtered-out current or frequency. That is, they cause the booster-transformer to have substantially no exciting-current, and hence substantially no magnetic flux and substantially no terminal voltage, across either its primary 13 or its secondary 17, with respect to the filtered-out current. This results in a considerable saving in the amount of transformer-iron which is needed for the transformer-core of the booster-transformer. When the filter-circuit is connected across the primary winding 13 of the booster-transformer, as shown at 22 in Fig. 1, the heavy fundamental-frequency load-currents are kept substantially entirely out of the booster-transformer, so that neither the primary winding 13 nor the secondary winding 17 needs to be designed to carry these heavy fundamental-frequency currents, thus saving materially in the cost and size of the booster-transformer. It may be noted, also, that the exclusion of the primary currents from the transformer, as by means of the filter-circuit 22, avoids any possibility of saturation-difficulties, due to either full-load currents or short-circuit conditions. But perhaps of even greater importance, my filters F in Fig. 1 avoid any possibility of excessive induced fundamental-frequency voltages in the booster-transformers.

It will be understood that the filter F, in Fig. 1, may be connected, either across the secondary winding, as shown at 21 in Fig. 1, or across the primary winding, as shown at 22 in Fig. 1, or some booster-transformers can be filtered in one way, while others are filtered in the other way, or both primary and secondary filtering-circuits may be used on each booster-transformer.

Since pilot-wire booster-transformer interference-preventing means, but without my filtering circuits, have been known for some time, having been extensively used in Sweden, for example, and since such systems have been fully explained in the technical press, a detailed explanation of the operation of my invention, as shown in Fig. 1, is not believed to be necessary, except to note that my addition of the filtering means makes the pilot-wire 11 effective to prevent or reduce inductive interference, only with respect to the harmonics, and not with respect to the fundamental-frequency currents. The fundamental-frequency currents are permitted to return in the normal or usual rail-and-ground return-path. To illustrate this operation, two different kinds of current-indicating arrows have been added, in Fig. 1, the full-line arrows representing the fundamental or filtered currents, while the dotted-stem arrows indicate the non-filtered harmonics. The auxiliary pilot-wire 11 carries only the harmonics, as represented by the dotted-stem arrows. At the track-connection 18 which is closest to the substation A, the harmonic currents which are carried by the auxiliary return-circuit wire 11 return to the track-rails 1, and thus return to the primary circuit of

the power-transformer 3, and thence they go out through the trolley-wire 2, as is indicated in Fig. 1.

Fig. 2 shows two modifications of the circuit which is shown in Fig. 1. The first modification is in the addition of a telephone-line voice-pass filter VP, in series with the telephone-circuit 8. This voice-pass filter VP substantially excludes all frequencies below the minimum frequencies necessary for satisfactory voice-reproduction. Such minimum frequencies may be 250 cycles, 300 cycles or 400 cycles, or the like, as has been previously explained. The voice-pass filter VP may permit the transmission of all frequencies higher than this lower limit, or it may, if desired, exclude certain unnecessary extremely high frequencies, such as all frequencies higher than anything in the order of 2,800 cycles or 4,000 cycles, more or less.

The second modification which is introduced in Fig. 2 is the replacement of the fundamental-frequency resonant-circuit filter F of Fig. 1, with a low-pass filter LP, which passes all frequencies which are substantially below the lowest frequency which is passed by the voice-pass filter VP of the telephone-wire. Otherwise, the operation of the Fig. 2 circuit is the same as that which has been described for Fig. 1, and no further explanation is believed to be necessary.

In Fig. 3, I show a modification of my invention in which, instead of using a harmonic-frequency pilot-wire return-path, I force the audible-frequency harmonic-currents to be confined substantially to the track-rails 1, without spreading out through the surrounding ground to any material extent, while at the same time permitting the fundamental-frequency or lowest-frequency return-currents to flow in their normal rail-and-ground paths. To this end, I connect the secondary circuits of the booster-transformers 15 across insulated gaps 1' in the track-rails 1. A fundamental-frequency or low-pass filter is connected across either the primary circuit or the secondary circuit of the booster-transformers 15, as indicated at F1 and F2, respectively, as will be understood from the discussions given in connection with Figs. 1 and 2.

The effect of this arrangement is to cause the booster-transformers 15, in Fig. 3, to develop whatever harmonic-frequency voltages there may be required in order to keep the harmonic-frequency current-flow, in the rails, equal and opposite to the harmonic-frequency current-flow in the trolley-wire 2, thereby forcing these harmonic currents to flow through the track-rails 1. I accomplish this result, however, without forcing the heavy fundamental-frequency currents to confine themselves to the track-rails 1 for their return-circuit path, thereby greatly reducing the burden on the booster-transformers 15, and also avoiding the excessive-voltage difficulties resulting from the heavy fundamental-frequency currents, as previously noted.

Fig. 4 shows an advantageous variation over the circuit shown in Fig. 1 or Fig. 2, in which I add an additional filtered terminal-based or station-based booster-transformer or transformers 15', and an additional terminal track-connection 18', at each of the various substations along the right-of-way, such as the substation A. This substation is represented as being located at some intermediate terminal or location in the railway-system, not at the extreme terminal or end of the system, so that it may deliver current to either the right or the left, to the trolley-wire 2. In Fig. 4, a three-winding 1-to-1 ratio station-based booster-transformer 15' is shown by way of illustration, having a primary winding 13, and two secondary windings 171 and 172, all having the same number of turns. In Fig. 4, the booster-primary 13 is connected in series with the power-transformer circuit 4, so that whatever current is supplied to the trolley-wire 2 by that substation will be carried by the primary winding 13 of the booster-transformer 15'. The booster-secondaries 171 and 172 are connected between the track-

connection 18' and the respective sides of a pilot-wire gap 11" which is provided in the pilot-wire 11 at the substation A. The filter F or LP of Fig. 1 or 2, or the filters F1 and/or F2 of Fig. 3, may be connected either across the primary winding 13 in Fig. 4 or across the respective secondary windings 171 and 172. By way of giving an example, a filter F1 is shown connected across the primary winding 13 of the booster-transformer 15'.

It is believed that the operation of the apparatus shown in Fig. 4 will be apparent from the foregoing explanations and from the various arrows which are shown in the figure. It will be noted that the station-based booster-transformer 15' forces the harmonic currents to leave the pilot-wire 11 right at the substation, through the track-connection 18', instead of returning through the next spaced track-connection 18 along the right-of-way, as in Figs. 1 and 2.

Fig. 5 is a modification of the Fig. 4 circuit, in which the spaced boosters 15, along the right-of-way, are omitted, and the station-based booster 15' has a sufficient volt-ampere rating to force the pilot-wire harmonic currents to return through the pilot-wire 11. In this form of embodiment of my invention, there will be some spreading-out of the pilot-wire harmonic currents, between the vehicle V and the station A, particularly if a very small pilot-wire 11 is used. Thus, these harmonic currents will flow partially in the parallel paths through the track-rails 1 and the ground, by reason of the spaced track-connections 18 along the right-of-way; but in many cases the operation of the Fig. 5 circuit will be good enough, and the additional cost of the Fig. 4 circuit will not be required. By way of illustration, the Fig. 5 circuit uses secondary-connected filters F2, instead of the primary-connected filter F1 of Fig. 4.

While I have shown several illustrative forms of embodiment of my invention, I wish it to be understood that I am not limited to these particular forms, as various combinations and substitutions of the illustrative equipments shown in the various figures may be made, or still other changes may be made by way of the addition or omission of refinements, and the substitution of equivalents, without departing from the essential features of my invention. I desire, therefore, that the appended claims shall be accorded the broadest construction consistent with their language.

I claim as my invention:

1. In an electrified railway-system including tracks which serve jointly as vehicle-supporting means and also, at least in part, as ground-return means, an insulatedly supported bare single-phase power-supply line disposed in a position suitable for supplying single-phase power to one or more electrically propelled vehicles riding on said tracks, and an inductively coupled communications-line adjacent to said power-supply line; the combination including one or more booster-transformers, each having a primary winding and a secondary winding electrically insulated from each other, a means for electrically connecting the primary winding of said booster-transformer in series-circuit relation with respect to said power-supply line, a means for providing a fixed return-circuit serially including the secondary winding of said booster-transformer, said fixed return-circuit being so located that the inductive effects of the currents carried by said fixed return-circuit materially cancel out the inductive effects of the corresponding currents carried by said power-supply line, with respect to inductive effects in said communications-line, and a shunt-connected filter-means for materially excluding at least the fundamental frequency of the power-supply line from at least one of the windings of said booster-transformer.

2. The invention as defined in claim 1, characterized by said fixed return-circuit being the tracks.

3. The invention as defined in claim 1, characterized by said power-supply line being an overhead trolley-

conductor, and said fixed return-circuit being an auxiliary overhead conductor adjacent to both the trolley-conductor and the telephone-line, in combination with means for connecting said auxiliary overhead conductor to the tracks at each of a plurality of spaced points.

4. The invention as defined in claim 1, characterized by said filter-means including a series-resonant circuit tuned approximately to the fundamental frequency of the power-supply line and connected in shunt relation to the booster-transformer.

5. The invention as defined in claim 4, characterized by such a series-resonant circuit being connected in shunt relation to the secondary winding of the booster-transformer.

6. The invention as defined in claim 4, characterized by such a series-resonant circuit being connected in shunt relation to the primary winding of the booster-transformer.

7. The invention as defined in claim 1, characterized by said filter-means being operative to materially exclude 20 the lower harmonics, as well as the fundamental, from at least one of the windings of the booster-transformer.

8. The invention as defined in claim 7, characterized by said filter-means including a means operating substantially like a low-frequency band-pass filter connected in 25 shunt relation to the booster-transformer.

9. The invention as defined in claim 8, characterized by such a low-frequency band-pass filter-means being connected in shunt relation to the secondary winding of 30 the booster-transformer.

20

30

471,380

10. The invention as defined in claim 8, characterized by such a low-frequency band-pass filter-means being connected in shunt relation to the primary winding of the booster-transformer.

11. The invention as defined in claim 1, in combination with a band-pass filter-means, serially included in the communications-line, for materially excluding, from said communications-line, at least all frequencies below the minimum frequency which is substantially necessary for the communications-line.

12. The invention as defined in claim 11, characterized by the filter-means of the booster-transformer being operative to materially exclude, from at least one of the windings of the booster-transformer, at least all frequencies substantially below said minimum frequency which is substantially necessary for the communications-line.
